(57) **CLAIM**

The ornamental design for a surface configuration of a rear bumper for a vehicle, as shown and described.

DESCRIPTION

This application is related to the following co-pending application, of the inventor, filed on even date herewith: application Ser. No. 29/253,242, entitled “Surface Configuration of a Vehicle, Toy, and/or Other Replicas”.

FIG. 1 is a right perspective view of a surface configuration of a rear bumper for a vehicle according to my novel design; FIG. 2 is a left perspective view thereof;

FIG. 3 is a front view thereof;

FIG. 4 is a right side view thereof; and,

FIG. 5 is a left side view thereof.

The broken lines are for illustrative purposes only and form no part of the claimed design.

1 Claim, 2 Drawing Sheets

FIG. 1

FIG. 2
